Patent No. 1,983,017
Issued Dec. 4, 1934
For an improved internal bottom construction for supporting the checkerwork in a blast-furnace stove, and for a method of building such a stove.

UNITED STATES PATENT OFFICE

1,983,017

BLAST-FURNACE STOVE

Andrew Bowland, Mount Lebanon, Pa.

Application October 9, 1933, Serial No. 692,767

11 Claims. (Cl. 263—19)

This invention is an improved internal bottom construction for supporting the checkerwork in a blast-furnace stove. It is intended to eliminate many of the troubles usually connected with the costly and cumbersome brick, cast-iron or steel constructions ordinarily used for this purpose.

Broadly speaking, this improved construction includes a supporting structure and a plurality of units supported by this structure in a horizontal plane and which themselves support the checkerwork so as to leave the latter's flues unobstructed. These units are each capable of movement in any horizontal direction without affecting the others or the supporting structure and collectively form a platform on which the checkerwork is built. Each unit is small in area as compared to that of the checkerwork's bottom.

One advantage of the above is that the units may be individually shifted to fit a checkerwork whose pattern or flue spacing deviates from that expected because of brick inaccuracies. Another is that both localized and distributed expansion and contraction of the checkerwork is accommodated by the supporting units which may shift individually or as a group to maintain proper registration therewith. As the units are relatively small as compared to the checkerwork, this shifting is confined to that part of the latter which is actually expanding or contracting without being transmitted to the parts not moving. Further, stresses cannot be transmitted from the checkerwork to the structure supporting the units.

The supporting structure mentioned may include vertical columns which rise from the floor of the stove and are provided with saddle members at their tops. Relatively short metal bars may rest in these members in end-to-end and laterally spaced relationship with their respective ends separated sufficiently to permit individual longitudinal expansion and contraction. Such movement of these metal bars is slight because of their shortness and the fact that individual movement is not transmitted from one to another, due to their respectively separated positions.

Each of the units mentioned may be a grid constructed from a few relatively short metal bars interfastened in spaced parallel relationship. The spacing of these bars is such that the rows of checker bricks may be registered with them when the checkerwork is being built, the bars being sufficiently narrow to permit some lateral shifting of the checkerwork without blocking its flues. Longitudinal shifting cannot, of course, cause trouble of this character. At the same time, the bars should be sufficiently wide to provide a

firm central support for the rows of bricks forming the checkerwork.

Since it is generally desirable to produce a checkerwork having its layers laterally interlocked, by arranging the bricks so they extend from one layer to another, the bars forming the grids may be made alternately high and low. Then the registering bricks in the bottom layer of the checkerwork will be supported in a similar relationship whereby the desired interlocking results throughout the whole.

A specific example and modifications of the new bottom construction are illustrated by the accompanying drawings, the various figures being as follows:

Figure 1, a vertical cross-section of a side-combustion two-pass blast-furnace stove;

Figure 2, a horizontal cross-section of this stove;

Figure 3, a cross-section from the line III—III of Figure 2;

Figure 4, a cross-section showing the side of the construction shown by Figure 3;

Figure 5, an enlarged portion taken from Figure 2;

Figure 6, an enlarged portion of the new bottom construction as applied to a center-combustion, two-pass stove, the entire structure of the stove not being shown because it is not needed to disclose the invention;

Figures 7 and 8, cross-sections taken from the lines VII—VII and VIII—VIII in Figure 6;

Figures 9 and 10, top and side views of a modification of the invention as applied to a center-pass, side-combustion stove; and

Figures 11 and 12, top and side views of a similar modification as applied to a two-pass, center-combustion stove.

Referring more particularly to these drawings, the side-combustion, two-pass stove illustrated by Figures 1 through 5 includes the usual shell 1, combustion chamber 2, dome 3 and checkerwork 4. Chimney and burner openings 5 and 6 are provided in the conventional manner.

The function of such a stove is so well known as to need little discussion. Briefly, a burner is fixed to the opening 6 and heats the checkerwork 4 by way of the chamber 2 and dome 3, the combustion products passing through the opening 5 to a chimney. When the checkerwork 4 is sufficiently heated the gas is shut off and the cold air to be heated is forced through the cold blast valve in through the bottom of the checker chamber and up through the checkerwork, by which the

air is heated, and then passes through the dome 3 and chamber 2 to the hot blast mains.

Now the stove being described has its checker-work supported in the manner already described.

- 5 That is to say, metal columns 7 rise from the base of the stove and have saddle members 8 at their tops. Relatively short metal bars or girders 9 rest in these members in end-to-end and laterally spaced relationship with their respective ends 10 separated sufficiently to permit individual expansion and contraction. In other words, the parts described provide flat surfaces arranged in a horizontal plane, or it may also be said that the bars 9 form a horizontal platform.
- 15 It is to be noted that the bars 9 simply rest in the saddle members 8 and are not fixed in position except by the force of gravity. Each of the bars may move individually without affecting the others, movement therefore being restricted to 20 those bars which may happen to expand or contract due to localized heating effects.

The grids 10 rest directly on the bars 9 and in some instances on projections 1^a which extend inwardly from the shell. Steel plates 11 may be 25 placed between these projections and the grids to provide for a proper bearing, it being assumed that these projections will be formed of brick.

Now it is to be particularly noted that the grids 10 are individually small as compared to the 30 checkerwork 4. This means that the grids are used in multiple in all directions to support the checkerwork. Further, these grids are respectively separated sufficiently to permit their individual expansion and contraction so that movement of 35 one will not necessarily affect the others. The grids are each an integral unit and are used in multiple to support the checker so that each grid automatically adjusts itself to changes of temperature. Also, this design having each grid unit 40 consisting usually of three to four bars, permits the latter to be placed directly under the middle of the corresponding three to four rows of checkers. Thus any variation in the size of the checkers is not increased from grid to grid, but is taken 45 up at each grid instead. These grids may directly support the checkerwork.

As so far described, the bottom construction is such that the load of the checkerwork is carried by the columns 7 through the bars 9 and 50 grids 10, both the latter being capable of individual movement in horizontal directions in each instance and also respecting each other. The structure is not tied together to form an integral unit as was heretofore customary, localized heating effects in the metal bottom and 55 the checkerwork therefore producing localized movement only and not being transmitted and magnified throughout the whole of the metal bottom structure.

60 It has been previously mentioned that the parts may all be made from standard rolled shapes. The drawings show this to be true, each of the columns consisting of a conventional H-beam 7^a having its flanges removed at its top so that 65 short lengths of a conventional angle-bar may be welded to its web and flanges to form the saddle. A plate or slab is welded to the bottom ends of the H-beams 7^a to form column bases. The bars 9 are also standard rolled shapes of such a familiar character as not to need comment.

To protect the columns against erosive action of the cold blast, the H-beams 7^a may be each 75 enclosed by a casing 7^b consisting of a piece of steel plate wrapped therearound with its abutting edges welded or otherwise interfastened. The

bottom of this casing is welded to the column and its top held steady by bars 7^c which fit tightly against the column sides but are not fastened to them, which permits of expansion and contraction of the casing independent of the column.

80

As to the grids 10, they also are formed from standard rolled bars 10^a which are parallelly arranged on their edges and interconnected by welded spacers 10^b. In each instance these bars are sufficiently short and are grouped in such manner as to maintain the small relationship of the grids as compared to the checkerwork. Also, the bars 10^a may be alternately high and low or arranged at differing levels so that the individual bricks 4^a of the checkerwork may be registered therewith to produce the lateral interlocking throughout. This high and low relationship may be obtained by using bars of different widths or depths, the alternate terminology being used depending upon whether the bars are 90 considered as rolled or as in position.

85

The center-combustion stove illustrated by Figures 6 through 8 has a construction similar to that already described. It is disclosed for the purpose of showing that the grids may be constructed to fit any type of stove and that the general construction as a whole is sufficiently flexible to enable its installation in the various types. Similar numerals are used, because the various parts are the same.

90

One feature not previously shown is the asbestos strips 10^c which are interposed between the bars 10^a and the bricks of the checkerwork 4. These provide a cushioning effect and eliminate the undesirable effects sometimes resulting 110 from rough-bottomed bricks. Any of the constructions disclosed may include such asbestos strips.

105

Figures 9 and 10 show a modification of the invention as applied to a side-combustion stove. 115 The chief difference between this and the constructions already described is the use of diagonally arranged bars 12 on which the bricks of the checkerwork are laid. This construction may prove advantageous in that it is possible to there- 120 by vary the character of a checkerwork by laying up its bricks in a different pattern.

110

A further feature of this modification is the lengths of flat bar 11^a which are interposed between the tops of the bars 9 and the grids. 125 This provides an increased bearing surface and may be desirable in some instances. Also, the angles 8 have somewhat shorter upstanding portions than has been previously shown, the bars 9 being interconnected by spacers 9^a to secure a 130 more stable construction. It is obvious that the individual bars forming the grids 10 may be all of equal widths or depths and the diagonal bars 12 provided in alternating widths or depths to secure the interlocked checkerwork usually de- 135 sired.

120

The center-combustion stove shown by Figures 11 and 12 is particularly distinguished in that bars 13 are arranged radially on the projections 1^a and therefore do not require the columns previously described. These bars may be interfastened by spacers 13^b. Then bars 14 are arranged over the supporting bars 13, the checkerwork being built directly on the former which may be 145 of different sizes to provide the different levels.

140

It is to be appreciated in all of the various constructions disclosed, that it is necessary to construct the various elements from differently lengthed bars to accommodate the different sec- 150

tions of the stove, it being kept in mind that the different types naturally have different shapes.

I claim:

1. A blast-furnace stove having an internal bottom construction including the combination of a supporting structure, a plurality of horizontal metal bars supported by said structure in spaced parallel relationship, asbestos strips laid on said metal bars and a checkerwork supported by said metal bars and with its individual bricks registering therewith and resting on said asbestos strips. 5
2. An internal bottom construction for a blast-furnace stove, including a plurality of laterally spaced bars arranged above the base of such a stove and carrying a plurality of checkerwork-supporting bars, the latter being freely positionable on the first named bars so that they can be moved to accommodate the flues of a checkerwork being built thereon and being in all instances 10 transversely arranged respecting the first named bars.
3. An internal bottom construction for a blast-furnace stove, including a plurality of laterally spaced bars arranged above the base of such a stove and carrying a plurality of checkerwork-supporting bars, the latter all being slidably arranged transversely on the first named bars and all being relatively short as compared to the maximum unbroken lateral extent of the checkerwork 15 which they are intended to support.
4. An internal bottom construction for a blast-furnace stove, including a plurality of laterally spaced bars arranged above the base of such a stove and transversely carrying a plurality of checkerwork-supporting bars that are laterally slidable thereon, the second named bars being characterized in that alternate ones are of greater widths than the others and in that they are all arranged on their edges so that alternate rows of 20 the individual bricks of a checkerwork built thereon will be vertically offset from those in other rows.
5. An internal bottom construction for a blast-furnace stove, including a plurality of laterally spaced bars arranged above the base of such a stove and transversely carrying a plurality of checkerwork-supporting bars that are laterally slidable thereon, the second named bars being characterized in that their upper surfaces are 25 sufficiently narrow so that when in registration with the individual bricks of a checkerwork built thereon they will not block any of its flues should some shifting of the same occur.
6. An internal bottom construction for a blast-furnace stove, including a plurality of laterally spaced bars arranged above the base of such a stove and carrying checkerwork-supporting grids, the latter each consisting of a plurality of bars 30 parallelly interconnected by spacers that are proportioned to space them so that the individual bricks of the checkerwork to be supported may be registered therewith, said grids being freely positionable on the first named bars so that they may be laterally shifted to accommodate the pattern of said checkerwork and being in all instances 35 transversely arranged respecting the first named bars.
7. An internal bottom construction for a blast-furnace stove, including a plurality of laterally spaced bars arranged above the base of such a stove and carrying checkerwork-supporting grids, the latter each consisting of a few bars that are relatively short as compared to the maximum unbroken lateral extent of the checkerwork to be 40 supported thereby and which are parallelly inter- 45
- connected by spacers that are proportioned to space them so that the individual bricks of said checkerwork can be registered therewith, said grids being freely positionable on the first named bars whereby they may be individually laterally shifted to accommodate the pattern of said checkerwork and being in all instances transversely arranged on the first named bars. 50
8. An internal bottom construction for a blast-furnace stove, including a plurality of laterally spaced parallel bars arranged above the base of such a stove and carrying a plurality of checkerwork-supporting grids, the latter each consisting of a few parallel bars that are relatively short as compared to the maximum unbroken lateral extent of the checkerwork to be supported thereby and of which alternate ones are wider than the others, these bars being all arranged on their edges and interconnected by spacers proportioned to space them so that the individual bricks of said checkerwork may be registered therewith and having upper surfaces that are sufficiently narrow respecting said bricks that slight lateral shifting of said checkers will not cause its flues to be blocked thereby, said grids being freely 55 positionable on the first named bars whereby they may be individually moved to accommodate the pattern of said checkerwork and being in all instances arranged on the first named bars so that the said interconnected bars of which they consist are transversely associated therewith. 60
9. An internal bottom construction for a blast-furnace stove, including a plurality of laterally spaced bars arranged above the base of such a stove and carrying a plurality of checkerwork-supporting grids having checkerwork flue openings, said grids being characterized in that they are constructed so that non-registration of said openings with the flues of a checkerwork in one direction is immaterial in that said flues cannot be thereby blocked and in that they are freely 65 positionable on the first named bars so that they may be moved therealong at right angles to said direction to bring their said openings into position for registration with the flues of said checkerwork. 70
10. An internal bottom construction for a blast-furnace stove, including a plurality of spaced columns upstanding from the base of such a stove, said columns consisting of H-beams having their flanges removed at their tops and short lengths of angle-bars welded to their webs and the terminating portions of their flanges, and flat bars arranged with their ends between the webs of said H-beams and said lengths of angle-bars welded thereto and with their edges resting on said angle-bars. 75
11. An internal bottom construction for a blast-furnace stove, including a plurality of spaced columns upstanding from the base of such a stove, said columns consisting of H-beams having their flanges removed at their tops and short lengths of angle-bars welded to their webs and the terminating portions of their flanges, and flat bars arranged with their ends between the webs of said H-beams and said lengths of angle-bars welded thereto and with their edges resting on said angle-bars, said H-beams being encased in steel plates which are wrapped there-around with their adjacent edges interconnected in each instance, said plates being capable of individual expansion and contraction respecting said H-beams. 80

ANDREW BOWLAND.
